A patent for the invention described and illustrated in the drawings
and claimed in the claims attached hereto is granted to the inventor
as follows:

UNITED STATES PATENT OFFICE

2,353,416

KNIFE

Louis Silver, San Francisco, Calif.

Application September 29, 1943, Serial No. 504,515

3 Claims. (Cl. 30—340)

This invention relates to a knife, and particularly to a knife of the dagger type, such as a combat knife or hunter knife, or the like.

An object of this invention is to provide a dagger type knife with a handle construction which locates the center of gravity of the entire knife well within that portion of the handle which is gripped in the palm of the hand, and which facilitates the control and manipulation of the knife blade as well as permits the use of the handle end of the knife as a bludgeon or for cracking or hitting an object.

Another object of this invention is to provide a knife of the character described which is highly useful and simple in construction. Convenience of arrangement, lightness and comparative inexpensive of manufacture are further objects which have been borne in mind in the production and development of the invention.

It will be understood that various changes in the details and materials of construction may be made without departing from the spirit or scope of the invention as defined by the appended claims.

With the foregoing and other objects in view, which will be made manifest in the following detailed description, reference is had to the accompanying drawing for the illustrative embodiments of the invention, wherein:

Fig. 1 is a side view of a knife constructed in accordance with my invention.

Fig. 2 is a sectional view of the handle portion of the knife.

Fig. 3 is a fragmental, sectional view of a modified form of my invention.

Knives of the dagger type now used in combat, or by hunters are so proportioned and balanced that the blade portion of the knife is much heavier than the handle portion. The center of gravity of such a knife is usually well within the blade, and frequently at about the longitudinal center or middle of knife, on about the broken line X shown in Fig. 1. When such knife is manipulated or handled with the speed required in self defense or danger the blade has a tendency to resist by its inertia the hand action and its controlling movement. Another disadvantage of a knife of the type heretofore used is that the knife becomes totally useless for anything if the blade breaks. Inasmuch as such knives are used in fighting at close quarters the breaking of the blade leaves the combatant without any weapon whatever.

These and other disadvantages of the knives heretofore used are obviated by my invention.

In carrying out my invention I make use of a blade 1 of the pointed or dagger type. From the thicker base 2 of this blade 1 extends a stem 3. In the herein illustration the stem 3 has a flat side to prevent rotation of the handle on it. On the stem 3 is mounted a handle 4 so formed as to comfortably fit into the palm of the hand. Between the base 2 of the blade 1 and the adjacent end of the handle 4 is secured a suitable hand guard 5.

10 The stem 3 has a shoulder 6 formed thereon in substantial registry with the free end 7 of the handle 4. A reduced end 8 extends from this stem shoulder 6 and beyond the free end 7 of the handle 4. A counterweight 9 is held on this reduced end 8 in any suitable manner, for example by flaring the outer end 10 of the reduced stem end 8 so as to press the base of the counterweight 9 against the free end 7 of the handle 4.

15 In the modified embodiment shown in Fig. 3 the counterweight is formed by a suitable outer shell 11 loaded with a heavier filler material 12, such as lead or the like.

The counterweight is of such shape that it 20 conveniently fits against the side of the hand outside of the palm and aids in holding the knife against slipping out of the palm. In this illustration the exterior shape of the counterweights is substantially that of a spherical ball with a flat flange base bearing against the free end of the handle. The weight of the counterweight is 25 so proportioned with respect to the weight of the blade that the handle is loaded well within the outermost end of the handle, namely, between the middle of the handle and its free end. The middle line of the handle, which is at about the one-fourth of the length of the knife with respect to the free end of the handle is indicated by a 30 broken line Y in Fig. 1. The center of gravity of the knife is in the one-fourth area between the line Y and the outer or free end of the handle. This balance assures full control of the knife within the palm of the hand of the user and facilitates direction and manipulation of the 35 knife. If the blade breaks, the handle portion is still useful as a bludgeon because the counterweight can be used with bludgeoning effect for striking and hitting with the fist closed. This 40 counterweight may be used thus even when the blade is intact for cracking or breaking or hammering any object as the occasion may require. The outer surface of the bludgeon counterweight is preferably tough material. In the form shown 45 in Fig. 3 the inside filler may be of softer substance.

I claim:

1. A knife of the character described comprising, a blade, a stem extended from the blade, a handle on the stem, and a bludgeon type counterweight on the stem adjacent the free end of the handle, the weight and location of said counterweight being so proportioned to the blade that the center of gravity of said knife is in said handle.

2. A knife of the character described, comprising a blade, a stem extended from the base of the blade, a handle on said stem, a guard between said handle and the base of the blade, and a bludgeon type counterweight on the end of the

stem at the other end of the handle, said counterweight and said blade being relatively so proportioned that the center of gravity of said knife is within the handle and spaced from said guard.

5 3. A knife of the character described comprising, a blade, a stem extended from the base of the blade, a handle on said stem, and a bludgeon type counterweight on the end of the stem at the free end of the handle being so proportioned 10 relatively to said blade that the center of gravity of the knife is within the half of the handle farthest from the base of the blade.

LOUIS SILVER.
